UNITED STATES PATENT OFFICE.

JOSEPH TOMLINSON, OF FOLSOM, CALIFORNIA.

WRENCH.

SPECIFICATION forming part of Letters Patent No. 398,989, dated March 5, 1889.

Application filed June 30, 1888. Serial No. 278,704. (Model.)

To all whom it may concern:

Be it known that I, JOSEPH TOMLINSON, of Folsom, in the county of Sacramento and State of California, have invented a new and useful 5 Improvement in Wrenches, of which the following is a specification.

My invention relates to improvements in that class of wrenches in which the jaws are pivoted within a frame or casing and are 10 caused to clamp the nut by a sliding handle engaging the rear ends of the said jaws.

The invention consists in the peculiar construction and arrangement of parts as hereinafter fully described, and pointed out in the 15 claim.

Reference is to be had to the accompanying drawings, forming a part of this specification, in which similar letters of reference indicate corresponding parts in all the figures.

20 Figure 1 is a plan view of my improvement. Fig. 2 is a sectional plan view, and Fig. 3 is a longitudinal section.

Referring to the drawings by letter, A represents the body of the wrench, which is composed of the top and bottom plates *a a'*. The bottom plate, *a'*, is provided at its rear 25 end with the upwardly-projecting flanges *a²*, which are reduced to pass through apertures in the top plate, *a*, and screw-threaded to receive the nuts *b*, by which the said plates are secured together. Between the plates *a a'* are pivoted the lever-jaws *B* by means of the bolts *H*, which pass through the said plates and are provided with the nuts *h*.

30 The forward ends of the lever-jaws *B* are constructed in the form as shown at their forward ends to adapt them to receive a nut, and their rear ends are curved outwardly, as shown. In order that the lever-jaws *B* may be held open and ready for use, a spring, *G*, 35 is interposed between the lever-jaws, with its ends engaging shoulders on the said lever-jaws. For operating the lever-jaws a sliding

bar, *C*, provided with the head *c*, projects into the body, and to the said head *c* are attached 45 the blocks *E*, which fit between the top and bottom plates of the body and are notched or recessed to receive the rear ends of the lever-jaws *B*. To the outer end of the bar *C* is detachably secured the handle *D* by means of 50 the spring-pressed catch *d*, pivoted in the handle and engaging a notch in the end of the bar *C*. By making the handle *D* removable it may be taken off and the wrench used with a bit-stock. 55

From the above-described construction it will readily be seen that the lever-jaws, which are normally held open by the spring, may be closed upon a nut by moving the sliding bar *C* inward, which movement will force the inner ends of the lever-jaws outward and cause them to clamp the nut. For clamping the sliding bar *C*, and thereby holding the same in the position to which it has been moved, a thumb-screw, *F*, is passed through the top 60 plate, *a*, so that its lower end will engage the said bar *C*. By this means the lever-jaws can be held locked in a closed position when desired. 65

Having thus described my invention, what I 70 claim, and desire to secure by Letters Patent, is—

In a wrench, the combination, with the body portion *A*, of the lever-jaws *B*, pivoted in and at the forward end of the body and having 75 outwardly-curved rear ends, the spring *G*, interposed between the lever-jaws for holding them open, the bar *C*, sliding within the body and provided with the head *c*, and the blocks *E*, secured to the head *c* and recessed to receive the rear ends of the lever-jaws, substantially as described. 80

JOSEPH TOMLINSON.
